UNITED STATES PATENT OFFICE.

THOMAS D. JONES, OF CLEVELAND, OHIO.

EMERGENCY-KNUCKLE.

No. 832,910.

Specification of Letters Patent.

Patented Oct. 9, 1906.

Application filed January 17, 1906. Serial No. 296,562.

To all whom it may concern:

Be it known that I, THOMAS D. JONES, a citizen of the United States, residing at Cleveland, in the county of Cuyahoga and State of Ohio, have invented new and useful Improvements in Emergency-Knuckles, of which the following is a specification.

This invention is an emergency-knuckle for railway-car couplings—that is, a knuckle 10 designed to be used in place of the ordinary knuckle when the latter is broken. It frequently happens that knuckles break, necessitating the temporary substitution of an emergency-knuckle.

15 The object of the present invention is to provide an emergency-knuckle which can be used with any of the standard draw-heads and which will be automatic in its operation and simple in its construction, and which will 20 not require any special devices for attaching the same to the draw-head or for holding the same coupled.

The invention is illustrated in the accompanying drawings, in which—

25 Figure 1 is a top plan view of one of the emergency-knuckles applied to a draw-head and coupled with another draw-head and knuckle of ordinary type. Fig. 2 is a plan view showing two of the emergency-knuckles 30 coupled together. Fig. 3 is a perspective view of a draw-head provided with one of the emergency-knuckles.

Referring specifically to the drawings, 6 indicates a draw-head and 7 a knuckle of the ordinary Janney or Master Car-Builders' type, pivoted to the draw-head by the pin 8. The emergency-knuckle consists of a curved or knuckled casting having a front or hook portion 9 and a rear portion 10 and a hole to receive the bolt 8, located at the rear outer corner or angle of the casting. The hook portion 9 is made of substantially similar size and shape to the hook of an ordinary knuckle, of length sufficient to throw the point of the hook beyond the center or line of draft, for the purpose of interlocking the emergency-knuckle in engagement with the knuckle of the other head. The rear portion 10 of the emergency-knuckle is made thick and heavy to give sufficient strength and is shaped to fit within the cavity 11 found in the standard draw-head and against the draw-head, thereby taking the impact off the pin. Said rear portion 10 extends laterally 55 beyond the end of the hook portion 9, and

when in use the end of said portion 10 bears against the rear or back side of the opposite knuckle at or about the point 12, and hence the pull on the hook 9 causes the emergency-knuckle to grip or lock with the opposite 60 knuckle and produce the coupling. The part 10 also acts as a striker to receive the impact of the opposite coupling and so throw the knuckle closed when the draw-heads come together.

65 The standard draw-heads vary in the configuration of the latches and other devices used to hold the knuckle closed. Consequently to allow the universal use of an emergency-knuckle it should be without any kind of 70 latch or fastening device, because what would fit one kind of head would not fit another. This emergency-knuckle herein described has no latch, being held closed by its peculiar configuration and by the extension 75 of the ends of its hook and its rear portion beyond the center line with the pivot offset to the side as far as possible. Consequently the pull comes between the end of the hook and the pivot and does not tend to open the knuckle. 80 This action is assisted and the lock assured by the bind of the rear portion 10 at the point 12. Hence it can be used on any kind of head.

85 In Fig. 2 I show two of the emergency-knuckles coupled. They will both hold without any fastening device or latch. In consequence, however, of the shape of the knuckle it is necessary in order to attach or detach two of the emergency-knuckles that 90 one of the pins 8 be withdrawn, as they are locked together when so set and will not unlock under pull. Thus to attach two of the emergency-knuckles together, one knuckle is removed from the draw-head and engaged 95 with the other knuckle. Then the draw-head is brought to the knuckle and the pin 8 inserted. To detach, one pin 8 is removed and the car and draw-head pulled away. This frees one knuckle and allows it to drop down 100 away from the other. In other words, vertical movement is essential to couple or uncouple two of the emergency-knuckles; but necessity for this very rarely arises.

105 I claim—

The combination with a draw-head of the Janney type having a cavity in its face, of an emergency-knuckle comprising a casting having a front hook portion adapted to engage within the opposite knuckle and a rear

portion adapted to bind against the outer side of the said knuckle, the casting being pivoted to the head at its rear outer corner, and the rear portion of the casting being shaped to fit within said cavity, and against the draw-head, so as to transmit the impact against said rear portion directly to the draw-head.

In testimony whereof I have signed my name to this specification in the presence of two subscribing witnesses.

THOMAS D. JONES.
